MULTIPLE COMPARTMENT MERCHANDISE DISPLAY

Filed Oct. 2, 1936

UNITED STATES PATENT OFFICE

2,097,635

MULTIPLE COMPARTMENT MERCHANDISE DISPLAY

Louis H. Mayo, Toledo, Ohio, assignor to The Toledo Show Case Company, Toledo, Ohio, a corporation of Ohio

Application October 2, 1936, Serial No. 103,837

2 Claims. (Cl. 312—118)

This invention relates to merchandise display sections.

This invention has utility when incorporated with quantities of bulk material adapted for sham display with adjacent separate compartments readily removable in fractional quantities.

Referring to the drawing:

Fig. 1 is a fragmentary view of a display showcase as for foodstuffs or confections;

- 10 Fig. 2 is a section on the line II—II, Fig. 1;
Fig. 3 is a section on the line III—III, Fig. 2;
Fig. 4 is a section on the line IV—IV, Fig. 2;
and

Fig. 5 is a perspective view of a secondary partition.

Show case adapted for retail merchandise display has deck 1, front molding 2, with transparency riser or glass 3 therefrom as the show case front of plate glass. Receding therefrom and parallel to the deck 1 is show case top 4 having anchoring means 5 assembling the glass top 4 with the glass front 3. The front 3 may be held against the molding 2 by spaced clips 6 on inclined deck portion 7. The deck 1 rearwardly has removable threshold 8, terminally engaging the entrance seat portions 9.

Adjacent the top 4, opposing seat 10 is provided permitting slide doors 11, 12, to slide by one another for access to show case interior 13.

- 30 In this show case interior 13, primary partitions 14 have lower edge 15 resting on the deck 1, front edge 16 for rest closely approaching the contour of the transparency front 3. Toward the top 4 in this compartment 13 and spaced a de-
35 sired distance from the deck 13, a partition 14 may have top edge 17 extending away from the front 3 toward rear entrance 18 as permitted by opening of the door 11 or 12. This primary partition 14 may have rear edge 19 desirably con-
40 figured against wounding the attendant and of a shape for desired bulk of merchandise between a pair of these parallel partitions 14.

These partitions 14 at the lower forward end and spaced therefrom are provided with interlocking means or projecting hooks 20 on each side thereof. Remote therefrom and slightly spaced from the edge 11, partitions 14 are provided with interlocking means or eyes 21.

In cooperation with one or more of these primary partitions, secondary partitions are disclosed herein, embodying riser 22 having lower edge 23 adjacent the deck 15 and desirably back from the inclined deck portion 7. This portion 22 of the secondary partition is effective to conceal the interlocking means 20 and has complementary interlocking means 24 interfitting there-

with. This riser 22, short of the edge 17, has receding portion 25 approximately parallel to the deck 15 and spaced from the edge 17 of the partition 14 but of an extent to have the interlocking means 21 therebelow. This secondary partition has complementary locking means 26 for entering the locking means 21, thereby providing a jacket for bulk compartment 27 below the secondary partition, with the edges 17, 16, of the primary partitions as beyond the portions 22, 25, of the secondary partitions, thereby forming a display compartment 28 for merchandise as viewed through the top 4 and the front 3, which quantities it may not be necessary to disturb fractionally in removing sales quantities of merchandise from the compartment 27 through rearward opening 29 thereto between the edges 19 of the primary partition. This display compartment 28 may have the merchandise more definitely held therein between the partitions 17 at its rearward portion by riser portion 30.

It is thus seen that in this assembly, the secondary partition may be lifted out independently of disturbing a primary partition on either side thereof, and this general display for merchandise is such that it may be a single unit of a desired extent at any location in the counter or throughout the extent of the counter or show case, if in a show case. 25

What is claimed and it is desired to secure by 30
Letters Patent is:

1. A pair of partitions each having seat means inward from two of its diverging edges, and a spacer for the partitions having complementary projections below one portion and at the rear of the other portion of the spacer for registering with the seat means to locate the spacer inset from the partition edges and providing an upward and horizontal clearance with the spacer as a support between the partitions, abutting each partition throughout the common extent therewith. 35 40

2. A showcase insert embodying a pair of partitions, each having a top edge and a forward edge, said partitions each having marginal clearance inward from one of said edges terminating in a socket and inward from the other of said edges, in a hook, and a spacer having opposing edges abutting each partition throughout the extent of the spacer intermediate the partitions, said spacer on the side thereof away from the clearance region of the partitions having complementary interlocking projections registering with the sockets and hooks to engage and lock the partitions in parallelism. 55
